(57) **CLAIM**

An ornamental design for a display unit with built-in shelving supports, as shown and described.

DESCRIPTION

This application is also related to the following design applications: U.S. Design patent application Ser. No. 29/588,433; U.S. Design patent application Ser. No. 29/588,435; U.S. Design patent application Ser. No. 29/588,436; U.S. Design patent application Ser. No. 29/588,438; U.S. Design patent application Ser. No. 29/588,440; U.S. Design patent application Ser. No. 29/588,441; U.S. Design patent application Ser. No. 29/588,442; U.S. Design patent application Ser. No. 29/588,443; and U.S. Design patent application Ser. No. 29/588,444. Each of these related design applications is hereby incorporated by reference in its entirety.

FIG. 1 is a perspective view of my new design for a display unit with built-in shelving supports;

FIG. 2 is a top view thereof.

FIG. 3 is a bottom view thereof.

FIG. 4 is a front view thereof.

FIG. 5 is a rear view thereof.

FIG. 6 is a first side view thereof; and,

FIG. 7 is a second side view thereof.

The broken lines in the Figures are for illustrative purposes only and form no part of the claimed design.
